WAVE SIGNALING SYSTEM

Harold M. Lewis, Douglaston, Long Island, N. Y.,
assignor to Hazeltine Corporation, a corpora-
tion of Delaware

Application May 6, 1931, Serial No. 535,328

16 Claims. (Cl. 178—5.6)

This invention relates to the simultaneous transmission and reception of a plurality of signals and more particularly to a system for the transmission and reception of signals wherein a receiving station can be adjusted to receive the plurality of signals transmitted from any of a number of transmitting stations.

A prime purpose of the invention is to provide a system wherein the plurality of signals simultaneously transmitted by a transmitting station comprises a signal corresponding to acoustic waves and a signal corresponding to visual, or television, waves.

In accordance with this invention, it is contemplated to so organize each transmitting and receiving station of the general system that any of the receiving stations can readily be adjusted to receive the simultaneous visual and acoustic program of any of the transmitting stations. In other words, by utilizing the principles of this invention, there can be developed a broadcast system of combined acoustic and visual programs, in a manner analogous to the present system for broadcasting and receiving acoustic programs.

The invention is effected by assigning to each of the transmitting stations of the general system definite frequencies for the carrier waves of the plurality of programs transmitted; there is, furthermore, assigned to the associated carrier waves of each station a certain ratio of frequencies which is the same for all the transmitting stations. The preferred manner of assigning to the associated carrier waves of each station the required definite ratio, is to utilize certain definite harmonics of a frequency determining element. Each of the carrier waves of a station is transmitted from an individual transmitting circuit.

The receiving stations of the general system of this invention comprise a plurality of receiving circuits corresponding to the transmitting circuits of the transmitting stations. Each of the receiving circuits of a receiving station is adapted to select and detect the modulated carrier signal radiated from the corresponding transmitting circuit of a transmitting station.

To enable any receiving station to be tuned to the transmitted signals of any transmitting station, each receiving channel, or circuit of the receiving station, is provided with one or more tunable circuits. The tunable circuits of each receiving channel are caused to vary in accordance with the same law of tuning control versus frequency variation between the same ratio of maximum to minimum frequency; and furthermore,

the ratio of the tuned frequencies of the plurality of receiving circuits remains constant over the range of operation and is equal to the ratio of the plurality of carrier frequencies of the transmitting stations.

In some embodiments of the invention, a separate antenna is employed for each channel of the receiving station; in other embodiments a common antenna is employed and the proper signals from the antenna are impressed upon the individual receiving circuits by means of appropriate input circuits.

In another embodiment of the invention, the receiving station is adapted to receive signals of a type in which only a single sideband and no carrier, for each signal, is transmitted. In this embodiment, the missing carriers are supplied by local oscillators. A feature of this arrangement is a means for tuning the receiving channel at the middle of the sideband when the associated local oscillator is tuned at the frequency of the missing carrier.

Another embodiment comprises a receiving station including superheterodyne receivers. This arrangement may be adapted for the single sideband transmission or for the usual type of transmission in which the carrier and both sidebands are transmitted.

The invention will be better understood from the following detailed description when read in conjunction with the drawings, of which:

Fig. 1 illustrates schematically a dual signal transmitting station in accordance with this invention;

Figs. 2 and 3 illustrate graphically on polar coordinates the method of frequency allocation employed in accordance with this invention in transmitting and receiving a plurality of signals simultaneously;

Fig. 4 illustrates schematically a receiving station, in accordance with this invention, adapted to receive the dual transmission signals from a transmitting station like that of Fig. 1;

Fig. 5 shows schematically a superheterodyne type of receiving station embodying the invention.

Since the invention is directed primarily to a system for the combined transmission of signals corresponding to vision and to sound, it will be the practice throughout this specification to refer to those frequencies having their origin in light as vision signals, or vision frequencies, and to those frequencies having their origin in sound, as sound or acoustic signals or frequencies. It is necessary to make this distinction owing to the

fact that the signals having their origin in sound occupy in part the same frequency range as signals having their origin in light, prior to modulation with the carrier frequency. For example, the sound frequency range is approximately 50-6,000 cycles per second, and the vision frequency range is approximately 16-50,000 cycles per second.

Fig. 1 illustrates schematically a transmitting station in accordance with this invention which is adapted to transmit simultaneously acoustic and vision signals. The individual elements of the station are illustrated in generalized form; since they are not novel in themselves, there is no point in illustrating or describing them in detail. The station comprises two branches, or channels, designated generally as 10 and 11, the upper branch of which is a circuit adapted to transmit vision frequency modulated signals and the lower branch of which is a circuit adapted to transmit acoustic frequency modulated signals. In this and following figures the subscript "v" designates apparatus associated with the vision circuit, and subscript "a" designates apparatus associated with the acoustic circuit.

The system comprises a frequency determining element 9, label F, which is connected with both the acoustic and vision circuits and is adapted to impress upon both these circuits oscillations of a definite fixed frequency. The frequency determining element may be any well-known arrangement for providing a constant frequency, such as a piezo electric crystal controlled oscillator.

The vision branch, or circuit, 10 of the station comprises a harmonic generator 12, for generating a certain harmonic of the frequency determining element 9, which is the carrier wave of the vision circuit. The vision carrier signal is amplified by an amplifier 13. The amplified carrier signals are impressed upon a modulator 14, upon which is also impressed signals from a second amplifier 15, which amplifies signals generated in a photo-electric cell 16 by means of a television scanning disc 17. The modulated output of modulator 14 is amplified by an amplifier 18. From the output of the latter amplifier the band of frequencies corresponding to a vision frequency modulated wave is radiated from an antenna 19.

The acoustic circuit 11 is arranged in a fashion analogous to the arrangement of the vision channel 10, the subscript "a" designating the elements of this circuit. The corresponding elements of the acoustic and of the vision circuits are designated by the same numerals except that in the case of the acoustic circuit the numerals are primed. In place of the scanning disc and photo-electric cell of the vision circuit, the acoustic circuit is provided with the usual microphone 20.

The operation of the individual vision and acoustic circuits 10 and 11 and the component elements of these circuits are well known in the art and require no extended discussion here.

One manner of allocating the respective vision and acoustic carrier frequencies in a general broadcasting system comprising many transmitting stations of the type illustrated in Fig. 1, is shown graphically in Fig. 2. Fig. 2 is a polar chart having three angular scales A, B and C. The inner scale A represents fundamental frequencies, that is, the frequencies of the frequency determining elements F of all the stations of the general broadcast system. For convenience, and

in order to provide a uniform frequency separation between the transmitting carrier signals of all the stations of the system, the separation between the generated frequencies of the elements F of the individual transmitting stations is made 2 kilocycles per second. Thus, if the frequency generated by the element F of a certain station be 100 kilocycles per second, the frequency of the corresponding element of F of a second station which radiates signals closest in the frequency spectrum to those of the first station, will be 102 kilocycles per second.

Scale B represents the acoustic carrier signal frequencies radiated from the acoustic circuits of the stations.

In the case of the particular arrangement of the broadcast stations now being described, the acoustic carrier frequency for all the stations is selected as the fifth harmonic of the fundamental frequency of the element F. This fifth harmonic is obtained by adjusting the selective amplifier circuit 13' associated with harmonic generator 12' to select the fifth harmonic of the element F.

Since the fifth harmonic has been selected as the acoustic carrier frequency, it follows that the separation between the acoustic carrier frequencies of the several stations of the system will be 10 kilocycles per second as in the case of the present day acoustic broadcasting. This 10-kilohertz station separation is illustrated by the cross-hatched section at 850 kilocycles on scale B, the width of this cross-hatched section being 10 kilocycles. The corresponding vision frequency separation is indicated by the width of the cross-hatched section at 3,060 kilocycles on scale C.

Scale C represents the vision carrier frequencies of the stations. In the present system the vision carrier frequencies are selected as the eighteenth harmonic of the frequency determining elements F. It likewise follows that the separation between adjacent vision carrier frequencies in this case is 36 kilocycles per second, which is adequate for transmitting a television image of moderate detail.

In this case the ratio K between the two carrier frequencies is a constant and is expressed by:

$$K = \frac{f_v}{f_a} = \frac{f \times 18}{f \times 5} = 3.6$$

where,

f_v represents the vision carrier frequency;

f_a represents the acoustic carrier frequency;

f represents the fundamental frequency of the frequency determining element.

Any other harmonic frequencies might be selected, it being only necessary that the relation between the two carrier frequencies shall be the ratio of two integers and hence a constant for all stations operated in accordance with the proposed system. It is, of course, desirable that the acoustic carrier frequencies of all stations of the general system should cover the present day broadcasting range of 500 to 1500 kilocycles per second, as illustrated by scale B of Fig. 2. It is further desirable that the vision carrier frequencies shall be high so that the frequency separation between adjacent channels is large, in order that an image of good detail may be reproduced.

Referring for the moment to Fig. 1, it should be noted that the harmonics of both the vision and of the acoustic circuits could be selected from a single harmonic generator instead of two separate harmonic generators, as illustrated. In case a single harmonic generator is employed,

there would be required in each of the transmitting circuits, a selective circuit for selecting the proper harmonic to be employed as the carrier frequency.

5 Furthermore, if the fundamental frequency of the frequency determining element F be chosen to be the correct frequency for the acoustic carrier wave, then the harmonic generator in the acoustic circuit may be omitted and the situation 10 is that illustrated graphically in Fig. 3.

Fig. 3 is a polar chart similar to Fig. 2. Scale D of Fig. 3 represents the range of fundamental frequencies of the frequency determining elements of all the transmitting stations, which in 15 this case are the acoustic carrier frequencies. Scale E represents the range of vision carrier frequencies in a case in which the third harmonic of the fundamental frequency is employed. In this case K equals 3, and the frequency separation 20 for the television carrier frequencies is 30 kilocycles per second since the frequency separation of the acoustic carrier frequencies is taken as 10 kilocycles per second. The outer scale G represents the range of vision carrier frequencies 25 when the tenth harmonic is selected; in this event the frequency separation of the vision carrier waves is 100 kilocycles per second. The widths of the cross-hatched sections indicate the frequency separations for the three scales, where 30 the carrier frequency separation of scale D is made 10 kilocycles per second.

As a specific example, suppose a transmitting station to have the acoustic carrier frequency set at 860 kilocycles per second; then, if it be not required that the quality of the television transmission be exceptionally good, the third harmonic may be selected for this purpose; that is, the vision carrier frequency will be 2580 kilocycles per second. On the other hand, for transmitting 40 an image of much finer detail, the tenth harmonic may be selected, thereby allowing a band width of 100 kilocycles per second, which will require a carrier frequency of 3600 kilocycles per second.

45 Regardless of which harmonic is selected as the vision carrier frequency, it is essential in order to provide a general broadcast system in accordance with this invention, in which the program from any transmitting station may be selected 50 by a receiving station by means of a single tuning arrangement, that the same harmonic be selected for the vision carrier frequency of each transmitting station.

The statement that the ratio between the transmitted carriers from any one station shall be the ratio of two integers, applies only to the arrangement in Fig. 1 where a common frequency determining element F is used. This arrangement has the distinct advantage that any variation of f_v produces corresponding changes in f_v and f_a without changing their ratio K. However, the invention may be practiced with individual, independent frequency determining elements for the vision and acoustic branches and the ratio of carrier 65 frequencies may be any number and need not necessarily be a harmonic ratio, provided that all stations in the system likewise have the same ratio between the carrier frequencies which they transmit.

70 Fig. 4 illustrates a receiving station adapted to receive programs broadcast from any of a number of stations like that of Fig. 1. The station comprises two main branches, or circuits, corresponding to the two transmission circuits of Fig. 1. The upper circuit 35 is the vision receiving cir-

cuit and the lower circuit 35' is the acoustic receiving circuit. Both circuits constitute in themselves individual receiving circuits such as are commonly employed in radio reception.

Referring to the acoustic branch 35', the circuit comprises a receiving antenna 21' connected to the input of a radio-frequency amplifier 22'. The radio-frequency amplifier is shown in symbolic form as comprising amplifier tubes 23' and 24', and selective circuits 25', 26' and 27'. The 10 output of the radio-frequency amplifier is connected to the input of a detector 28', the output of which is connected through the usual audio-frequency amplifier 29' to a loud speaker 30'.

A local oscillator 31' is shown in dotted lines 15 associated with the detector 28'. For the present system in which signals are transmitted by means of modulated carrier signals, the local oscillator is not required; the necessity for the oscillator only rises in the case of a transmission system in 20 which only the side bands, without the carrier, are transmitted; such a system will be described subsequently.

The vision circuit of the receiving station is 25 analogous to the acoustic system, and the corresponding elements are similarly numbered except that in the case of the vision system, the numbers are not primed. Moreover, since the frequency range of the vision signals is different from that of the acoustic signals, the amplifiers 30 22 and 29 are adapted to transmit a different range than the corresponding amplifiers 22' and 29' of the acoustic circuit. Moreover, in the vision system a light valve 30 and the usual associated scanning disc 32 are used in place of the 35 loud speaker 30'.

The selective circuits of the vision and acoustic 40 receiving circuits are provided with a uni-control arrangement 33 which is operatively connected to the selective circuits of the two receiving circuits for allowing simultaneous tuning of the two circuits.

It will be assumed for the moment that the transmission from both the acoustic and vision branches of the transmitting station of Fig. 1 is by means of the usual modulated carrier waves, that is, a carrier and both side bands. Furthermore, it is assumed that both the acoustic and the vision carrier frequencies transmitted to the station have the harmonic relation previously described. Then, in order for the receiving station of Fig. 2 to receive simultaneously the vision and acoustic program, the same harmonic relation must exist between the resonant frequencies to which the two branches of the receiver 45 are tuned. Since, in accordance with the general broadcast system contemplated herein, there are other transmitting stations transmitting a dual program of vision and sound in a manner similar to that of Fig. 1, and also employing the same harmonic relationship or ratio between acoustic and vision carrier frequencies, it is essential, in order that the receiver may be tuned to select the program of any one of these stations by means of the single control device 33, 50 55 that certain conditions as to the circuit elements, both fixed and variable, be determined and maintained.

In the first place, all the transmitters should 60 be assigned carrier frequencies within a certain broadcast band of frequencies, in the manner illustrated in the charts of Figs. 2 and 3. The receiving station must then be equipped with variable tuning circuits adapted to tune over this entire broadcast frequency band. If, for exam- 65 70 75

ple, the tuning system for the acoustic receiving branch is arranged to tune between the frequency limits of 500 to 1500 kilocycles per second, as in present day broadcasting, that is, a three-to-one frequency range, then the tuning circuits for the vision receiving branch must be adapted to tune over the same three-to-one range of frequency variation, and its total range will be determined by the particular ratio of carrier frequencies selected. For example, where a ratio of ten is employed, the range of vision carrier frequencies will extend from 5000 to 15,000 kilocycles per second.

Another requirement is that the law of frequency variation with movement of the control device 33 must be the same for both the acoustic and the vision receiving systems. For example, the law of variation may be of any of the well-known types such as, "straight-line frequency", "straight-line capacity", and "logarithmic", or "hyperbolic".

It will therefore be clear that in fulfilling the two requirements, (1) by making the variable tuning elements of both branches similar in their law of frequency variation with control, and (2) by making the relation of maximum to minimum frequency over which they tune the same for both branches, it then follows that the proper relative choice of the fixed constants of the tuned circuits of the two branches will determine the ratio K of the two branches to be the same as that of the two carrier frequencies being received from any of the transmitters of the system. Furthermore, the ratio K will be maintained constant for any position of the control knob 33 as it is rotated to simultaneously vary the tuning of branches 35 and 35'.

In the operation, then, it is simply necessary to tune the receiver until the maximum acoustic reception is obtained and automatically the vision image will be simultaneously tuned in.

The easiest method of fulfilling the single control requirements of the situation described above is to employ in the selective circuits interleaving plate condensers having similar plates so that their laws of variation are the same, and to adjust the minimum circuit capacities so that all condensers operate in accordance with the same law of variation between the maximum and minimum capacity limits required by the particular range of tuned frequencies employed. For example, regardless of absolute values of capacity, in order to realize a maximum frequency variation of 3 to 1, all the tuning condensers would be required to provide a capacity variation of 9 to 1; this assumes that the associated inductances are fixed. The tuning condensers of the vision radio-frequency amplifier 22 would preferably be all alike, as would also the tuning condensers of the acoustic radio-frequency amplifier 22'.

It should be understood, of course, that the tuning could be accomplished by means of variable inductances instead of variable capacities, or else, both variable inductances and variable capacities might be utilized. It would further be possible to obtain identical laws of frequency variation by utilizing dissimilar tuning elements and then correcting for the dissimilarity by means of a cam or other non-linear mechanical link between the mechanical tuning control 33 and the variable tuning elements.

In addition to the transmission system just described in which the signals are transmitted by means of a carrier wave and two associated

side bands, there is also known an improved form of transmission, known as "single side-band" transmission, which has among other advantages the advantage that no carrier frequency is radiated from the transmitter; the only radiation is that of a single side band.

This form of transmission could be obtained in the transmitting station of Fig. 1 by the inclusion of appropriate filters and balanced circuits for suppressing the carriers and the unwanted side bands.

By virtue of the fact that there is present no relatively strong carrier signal, there are eliminated to a large extent disturbances due to interference of the carrier signal with other waves. A further advantage is that the side-band width may be doubled where there are utilized frequency transmission channels of the same width, thereby providing greater intelligence definition. In such a communication system it is necessary to supply the carrier signal locally at the receiver so that the modulation of the incoming side band with the local carrier wave will yield the original signal frequencies.

The receiving station of Fig. 4 may be readily adapted to receive signals transmitted by the single side band system. This may be accomplished by adding the local oscillators 31 and 31', respectively, illustrated symbolically by dotted lines, to the vision and acoustic circuits. Each of these local oscillators has a tuning circuit 34 and 34', respectively, for adjusting the oscillator to the proper carrier frequency. These oscillator tuning circuits are connected with the unit-control 33 in such a manner that each oscillator is tuned to the same frequency to which the radio-frequency amplifier of the associated branch is tuned. The band of frequencies transmitted by the radio-frequency amplifier at each tuning point is broad enough so that the entire side band is transmitted throughout. The side band combines with the locally generated frequency in the detector in the well-known manner to yield in the output of the detector the original vision or acoustic signals.

In the above instance, the full advantage of the width of the resonance band of the vision radio-frequency amplifier 22 is not realized since the resonant frequency is at the edge rather than at the middle of the side band of frequencies being received. It is desirable, especially for television purposes, to tune the radio-frequency amplifier at the middle of the side band in order that a broad range of side band frequencies may be transmitted. This latter desired condition may be obtained by keeping the ratio K constant as before, between the tuning of 31 and 31', but at the same time maintaining a predetermined frequency difference between the oscillator frequency and the tuning frequency of the radio-frequency amplifier. This frequency difference should be about half the sideband width, the frequency of the amplifier being either uniformly higher or lower than the frequency of its local oscillator according to whether the single side band transmitted is the upper or the lower side band.

For example, assume that the upper side band be transmitted by all the television branches of each transmitter, the lower side band and the carrier being suppressed, and that the television side band width is 100 kilocycles per second. Then the tuning of the radio-frequency amplifier should be arranged with respect to the tuning circuit of the local oscillator so that the fre-

5 frequency generated by the oscillator is 50 kilocycles per second below the frequency to which the radio-frequency amplifier is tuned. The frequency difference between the oscillator and the 10 radio-frequency amplifier must be maintained constant throughout the tuning range of operation.

Such maintenance of a predetermined frequency difference between the tuning circuits 15 of the radio-frequency amplifier and of the local oscillator may be readily realized by using for the variable tuning elements apparatus characterized by "straight-line frequency" type of tuning. For example, the use of variable condensers with plates so shaped that the law of frequency variation with angular movement of the plates is linear, provides this relation; hence, the fixed frequency difference may be provided for by setting the plates of the tuning condenser 20 of the oscillator at such an angle relative to the plates of the radio-frequency amplifier tuning condensers that there exists between the respective resonant frequencies the desired frequency difference.

25 Another method of obtaining the desired frequency difference between the oscillator and radio-frequency amplifier is to employ a fixed capacity in conjunction with the variable condenser. All the variable condensers would in this case 30 be identical for both the radio-frequency amplifier and for the local oscillator.

When single side-band transmission is employed for both the vision and the acoustic broadcast, it is preferable to arrange all the transmitters 35 so that all television and acoustic branches will always transmit the upper side band only, or conversely all will transmit the lower side band only.

40 Regardless of whether or not any or all of the carrier frequencies of a transmitting station are suppressed prior to radiation from the antenna, it is essential in the specific embodiments described that the carrier frequencies shall bear to each other the same constant ratio K.

45 Fig. 5 illustrates a dual program receiving station of which the individual receivers are of the superheterodyne type. The station comprises two circuits, or branches, 50 and 50' for television and acoustic reception, respectively. The 50 acoustic reception circuit comprises a radio-frequency amplifier 51' which is similar to radio-frequency amplifier 22' of Fig. 4. The output of amplifier 51' is transmitted to a first detector 52' with which is also associated a local oscillator 53'. 55 As a result of the combination in the first detector of the local oscillator frequency and the signal frequency at the output of the radio-frequency amplifier, there is produced at the output of the first detector the well-known modulation products which includes 60 the frequencies which represent the difference between the signal frequencies and the local oscillator frequencies. These difference frequencies which are produced in superheterodyne types 65 of receivers are commonly called intermediate frequencies. The intermediate frequencies are properly selected and amplified by an intermediate frequency amplifier 54', the output of which is impressed upon a second detector 55'. The 70 second detector operates in the well-known manner to produce at its output the audio-frequency component, which is amplified by an audio-frequency amplifier 56', and applied to a loud speaker 57'.

75 The television receiving circuit 50 is arranged

in the same manner as the acoustic receiving circuit 50', except that the usual light valve 58 and scanner 59 are incorporated in place of the loud speaker 57' of the acoustic circuit.

In the arrangement of Fig. 5 there is employed 5 a single antenna 60 which intercepts and supplies, simultaneously, vision signals to the vision receiving branch, and acoustic signals to the acoustic receiving branch. The two branches are effectively connected in parallel with the circuit 10 comprising the antenna 60 and ground 61. One of these parallel antenna circuit connections, namely, the one which includes the input to the vision circuit, includes a band pass filter 62 which freely transmits the entire range of the 15 vision signals transmitted by all the transmitting stations of the general broadcast system, but greatly attenuates all other frequencies including the acoustic broadcast range. Likewise, the antenna circuit connection which includes the input of the acoustic receiver includes in series 20 therewith a band-pass filter 63 which freely transmits the entire acoustic broadcast range, but greatly attenuates all other frequencies including the vision broadcast range. In this 25 manner the acoustic and vision signals are effectively confined to their respective receiving circuits. The receiver is provided with a uni-control arrangement 64 which operates upon the selective circuits of radio-frequency amplifiers 30 51 and 51' and of oscillators 53 and 53' in the manner described in connection with Fig. 4.

For uni-control operation, the necessary conditions to be maintained are that

$$\frac{f_v}{f_a} = K,$$

35

as indicated previously, and also that the following relations be maintained:

$$f_v - f_{ov} = f_{iv} \quad (2)$$

and

$$f_a - f_{oa} = f_{ia} \quad (3)$$

where

f_{ov} represents the frequency generated by oscillator 53;

f_{oa} represents the frequency generated by oscillator 53';

f_{iv} represents the frequency to which intermediate frequency amplifier 54 is tuned;

and

f_{ia} represents the frequency to which intermediate frequency amplifier 54' is tuned.

The above equations represent the condition 55 in which the local oscillators are tuned to frequencies lower than those of the associated carrier waves.

The receiving apparatus may be enclosed in a cabinet represented by the enclosures 66. Other well-known refinements may be incorporated, such as a rectified filtered source of alternating current for supplying the electrode potentials to the vacuum tubes.

In the event that the single side band type of transmission is employed, the missing carrier frequency may be furnished in the manner described in connection with Fig. 4, that is, an additional local oscillator may be associated with each of the first detectors 52 and 52'. A simple procedure, however, is to provide only a single oscillator for this purpose, such as the oscillator 65 indicated in broken lines; the output of this oscillator is connected to both detectors 55 and 55'. This arrangement, which utilizes only a single local oscillator for supplying the missing 75

carrier frequency, however, requires that the intermediate frequency amplifiers 54 and 54' shall transmit the same intermediate frequencies. It should be noted that in this arrangement where-
5 in the missing carrier frequency is supplied at the second detector, the local oscillator used to supply it is adjusted to generate, not the radio-frequency carrier frequencies, but rather the intermediate carrier frequency which is constant.
10 In the arrangement just described in which the intermediate carrier frequency is supplied at the second detector, it is still desirable that the radio-frequency amplifiers shall tune at the middle of the side band. This may be accomplished
15 by the method described in connection with the receiver of Fig. 4. For the case where only the upper side bands are being transmitted the relation to be maintained then is:

$$20 \quad fs_v = fv + f_1$$

$$fs_a = fa + f_2$$

and

$$fv = K = \frac{fs_v - f_1}{fs_a - f_2}$$

25 where

- fv* is the suppressed carrier of the vision transmitter
fa is the suppressed carrier of the acoustic transmitter
30 *fs_v* is the middle frequency of the vision side band
fs_a is the middle frequency of the acoustic side band
35 *f₁* is the middle frequency of the vision signaling frequencies
f₂ is the middle frequency of the acoustic signaling frequencies

Although the invention has been specifically described in respect to the dual transmission and reception of television and acoustic programs, it should be understood that the invention extends as well to the transmission of other types of programs. In other words, this system of broadcast transmission and reception is applicable whenever it is desired for any reason to separately transmit the several component parts of a unified performance. Furthermore, it is possible to transmit and receive more than two programs simultaneously by increasing accordingly the number of branches of the transmitters and receivers. For example, more channels would be required if voice and television in color are to be broadcast. One channel would then be required for the acoustic signals, another for the vision signals of one component color and a third for the vision signals of another component color. In the latter event the arrangement of the transmitting frequency ranges would be similar to 60 that of Fig. 3 wherein the carrier frequencies of the three transmitting programs are in accordance with the three scales of the figure.

It should be further understood that although radio transmission has been specifically described, the invention is equally applicable to any system of carrier transmission, including wire transmission.

What is claimed is:

1. A broadcasting system comprising a plurality of transmitting stations, each of said stations including means for transmitting a plurality of interrelated signals each of which is a part of a unified performance, said plurality of signals transmitted by each station bearing the 70 same harmonic relation to each other, and a

receiving station equipped with tunable means for simultaneously and separately selecting from a plurality of bands in frequency, signals from each band having said harmonic relation to each other, whereby each of said plurality of signals transmitted by any one of said transmitting stations may be simultaneously and separately utilized at said receiving station to reproduce said unified performance.

2. A system of broadcasting, comprising at 10 least two transmitting stations and at least one receiving station, each of said transmitting stations including means for simultaneously transmitting a plurality of signals each of which is part of a unified performance, the constant carrier frequencies of each of which bear the same fixed percentage relation to each other and said receiving station comprising means for simultaneously selecting and individually and simultaneously reproducing intelligence corresponding to the signals from any one of said transmitting stations to reproduce said unified performance, said selecting means comprising a uni-control arrangement which simultaneously adjusts a separate tuning circuit in resonance with 15 each of said signals from one of said transmitting stations.

3. A system of broadcasting which comprises a plurality of transmitting stations and at least one receiving station, each of said transmitting stations including means for simultaneously transmitting the component parts of a unified performance as a plurality of signals each of which has a carrier wave, each of the carrier waves of each station bearing a fixed ratio relation to each other which is the same for all the transmitting stations of said broadcasting system, and said receiving station comprising means for individually selecting said signals and means for individually and simultaneously reproducing 30 intelligence corresponding to each of said plurality of signals to reproduce said unified performance, said selecting means comprising a uni-control arrangement which is adapted to cause the resonant frequencies of said individual 35 selecting means to bear the same ratio relation to each other, over a large range of uni-control operation, as said carrier waves bear to each other, whereby said receiving station may be 40 tuned to select the signals from any of the transmitting stations.

4. A radio receiving system for simultaneously receiving signals corresponding to sound and signals corresponding to vision, which signals occupy frequency bands which bear a definite 55 harmonic relation to each other, comprising a receiving circuit for said vision signals and a receiving circuit for said acoustic signals, each of said circuits including a radio-frequency amplifier having associated therewith adjustable 60 tuning circuits, and uni-control means connected with said tuning circuits in such a manner that throughout the range of operation of said uni-control the tuned frequencies of said acoustic circuit and of said vision circuits bear 65 the said harmonic relation to each other.

5. A radio receiving system for simultaneously receiving signals corresponding to vision and signals corresponding to acoustic waves, comprising a receiving circuit for said vision signals 70 and a receiving circuit for said acoustic signals, each of said receiving circuits including a variable frequency-selecting circuit, a local oscillator having a variable circuit for tuning its output frequency and a detector associated with 75

5 said selecting circuit and with said local oscillator, whereby said signals modulate with the waves from said local oscillator in said detector, and uni-control means connected to the variable 5 selective circuit and to the variable tuning circuit of the oscillator of each receiving circuit in such relation that there is a fixed ratio between the tuned frequencies of the selective circuits of said receiving circuits, and a constant difference 10 maintained between each local oscillator frequency and the associated selective circuit frequency.

6. A radio receiving system for the simultaneous 15 reception of broadcast signals corresponding to sound and to vision, said broadcast signals being of the type in which the carrier wave is suppressed and only a single side band corresponding to each signal is transmitted, said system comprising a receiving circuit for the signals 20 corresponding to vision and a receiving circuit for the signals corresponding to sound, each of said circuits including a signal selecting circuit, a variable-frequency local oscillator having a variable tuning circuit and a modulator associated 25 with said signal selecting circuit and with said local oscillator, and uni-control means operatively connected with the signal selecting circuits and local oscillator tuning circuits of both 30 of said receiving circuits, in such relation that when the vision receiving circuit oscillator is tuned to the frequency of the suppressed vision carrier wave, the sound receiving circuit oscillator is tuned to the frequency of the suppressed sound carrier wave and said signal selecting circuits are tuned respectively to the vision and 35 sound frequency sidebands.

7. A system for the simultaneous reception of a plurality of signals, each of said signals bearing a fixed relation to each other, said system comprising a plurality of receiving circuits of the superheterodyne type, corresponding to the number of signals to be simultaneously received, each of said superheterodyne circuits including a signal frequency variable tuning circuit, a first 45 modulator coupled to said tuning circuit, a local oscillator having a frequency-determining circuit, coupled to said modulator, a tuned intermediate frequency amplifier for amplifying the modulation product of said oscillator frequency and 50 said signal frequency, a second detector connected to the output of said intermediate frequency amplifier and uni-control means operatively connected with said tuning circuit and with said frequency determining circuit of each 55 superheterodyne circuit in a manner to maintain said fixed relation between the tuning frequencies of said tuning circuits and to simultaneously adjust the frequency-determining circuits of said local oscillators so that the modulation products 60 are within the frequency ranges of said tuned intermediate frequency amplifiers.

8. A system in accordance with claim 7 in which said received signals are of the type in which only a single side band corresponding to 65 each signal, and no carrier, is received, and a second local oscillator associated with each of said second detectors, the frequency of each of said second oscillators being adjusted to be that of the intermediate frequency of the associated 70 superheterodyne receiving circuit.

9. A system in accordance with claim 7 in which said signals are of the type in which only a single side band corresponding to each signal, and no carrier, is transmitted, and the frequency 75 determining circuits of said local oscillators are

adjusted so that the intermediate frequencies of all said superheterodyne receiving circuits are the same, and a single second local oscillator, connected with all of the said second detectors, the frequency of said second oscillator being 5 equal to the intermediate frequency.

10. A radio receiving station adapted to receive simultaneously at least two signals, said station comprising an individual receiving circuit for each of said signals, tuning means associated 10 with each of said circuits and a uni-control device for simultaneously operating the tuning means of said circuits from a maximum to a minimum tuning frequency which is different for each of said circuits, the ratio of maximum 15 to minimum, and also the law of frequency variation with uni-control movement being the same for each of said tuning means.

11. A radio receiving station comprising a plurality of receiving circuits adapted to simultaneously receive and reproduce intelligence, each of said circuits including means for tuning over a band in frequency, and uni-control means connected with said tuning means, the fixed and variable circuit constants of both circuits being 25 chosen so that the ratio of the frequencies to which the two circuits are resonant is constant as the uni-control means is varied to tune each circuit over its respective band in frequency.

12. A system of broadcasting comprising at 30 least two transmitting stations and at least one receiving station, each of said transmitting stations including means for simultaneously transmitting a plurality of signals, and each receiving station being adapted to receive each of the signals transmitted by one of said transmitting stations, said receiving stations each comprising individual receiving circuits for each of said signals, tuning means associated with each of said circuits and a uni-control means for simultaneously 35 operating the tuning means of said circuits, the ratio of the adjacent frequencies of the various signals transmitted by each transmitting station being the same, and the fixed and variable constants of each receiving circuit being chosen 40 so that the ratio of the frequency of each signal to that of the adjacent signal being received is the same, and the same as that of the signals transmitted by each of said transmitters.

13. A radio receiving system for simultaneously receiving signals in a plurality of signal channels, said signal channels occupying frequency bands which bear a definite harmonic relation to each other, comprising a receiving circuit for each of said channels, each of said circuits including a tunable frequency selecting system, and uni-control means connected with said frequency selecting circuits in such a manner that throughout the range of operation of said uni-control the tuned frequencies of said 55 plurality of signal channels bear the said harmonic relation to each other.

14. A radio receiving system for simultaneously receiving signals corresponding to sound and signals corresponding to vision, which signals occupy frequency bands which bear a definite harmonic relation to each other, comprising a receiving circuit for said vision signals and a receiving circuit for said acoustic signals, each of said circuits including a frequency selecting circuit having associated therewith an adjustable tuning element, and uni-control means connected 65 with said tuning elements in such a manner that throughout the range of operation of said uni-control means the tuned frequencies of said 70 75

acoustic circuit and of said vision circuit bear the said harmonic relation to each other.

15. In a television system; a plurality of broadcasting stations for transmitting television and sound signals; means whereby each of said stations transmits carrier currents modulated by said sound signals and second carrier currents modulated by television signals, said television carrier at each station being separated from the sound carrier at the same station by a number of signaling channels of other of such stations; a receiving system including circuit means for picking up said television modulated carrier currents and circuit means for picking up said sound modulated carrier currents, each of said circuit means including a condenser having the characteristic of varying the frequency of their respective tuned circuits the same amount per predetermined angular rotation at substantially all the positions of the condenser; and a single means for operating said condensers simultaneously through the same angles.

16. The method of operating a television and sound broadcasting system which comprises transmitting a predetermined television carrier and transmitting a predetermined sound carrier of a different frequency than the television carrier and spaced therefrom a plurality of signaling bands; maintaining the predetermined fixed frequency relation between the carrier of the television signals and the carrier of the corresponding sound signals for each broadcasting station; operating two receivers to maintain a predetermined fixed frequency relation between them corresponding to the frequency relation of the television and sound carriers; operating the receivers to simultaneously tune in to a predetermined television and sound carrier station; and switching the receiver to a different transmitter of television and sound carrier while maintaining the frequency relation between the receivers.
